UNITED STATES PATENT OFFICE.

THOMAS E. JONES, OF PERU, INDIANA, ASSIGNOR OF ONE-HALF TO LLOYD M. STUMP,
OF PLYMOUTH, INDIANA.

BATTERY-STRAP MOLD.

Application filed March 1, 1922. Serial No. 540,254.

To all whom it may concern:

Be it known that I, THOMAS E. JONES, a citizen of the United States, residing at Peru, in the county of Miami and State of Indiana, 5 have invented certain new and useful Improvements in Battery-Strap Molds, of which the following is a specification.

This invention appertains to certain improvements in mold devices or apparatus 10 generally, and more particularly to a type of the same adapted for the rapid and accurate casting or molding of connector straps for electric storage batteries.

The principal object of the invention is to 15 provide for a molding apparatus of the class described, and one of an extremely simplified and durable construction and arrangement of parts, wherein is embodied certain novel features of adjustment for the 20 making of battery straps of different sizes with equal facility, and in a rapid and accurate manner.

Another object of the invention is to provide for an apparatus of the class set forth, 25 and one wherein the casted or molded article is to be readily ejected from the mold casting in a single operation of a manually actuated mechanism, and is then delivered from its ejected position on the mold into a suitable receptacle or the like at one side thereof by the resetting of the parts of the mold for a succeeding casting or molding operation, 30 all in a manner whereby the necessity of handling the hot mold or article by the operator is avoided.

With the foregoing and other objects in view, the invention resides in a certain new, novel and useful construction and arrangement of parts as will be hereinafter more 35 fully described, set forth in the appended claims, and illustrated in the accompanying drawings, in which:—

Figure 1 is a top plan view of a preferred embodiment of the molding apparatus in its 40 position ready for the pouring of the molten metal therein.

Fig. 2 is a similar view thereof with the cast or ingate of the same moved to its 45 operative or open position, and showing the interior of the mold body and the plungers therein for affecting the ejection of a strap 50 passing therefrom,

Fig. 3 is a front elevation, partly broken away to show the manner of securing one of the end blocks in position on the mold base, 55

Fig. 4 is a longitudinal section taken on the line 4—4 of Fig. 1,

Fig. 5 is a transverse section taken on the line 5—5 of Fig. 1,

Fig. 6 is a similar section taken on the 60 line 6—6 of Fig. 1,

Fig. 7 is a top plan view of the mold base per se,

Fig. 8 is a vertical transverse section 65 through one of the mold blocks, and showing the inclined wall formation of the mold cavity and core piece thereof, and,

Fig. 9 is a face view of one of the mold block inserts.

Referring to the drawings, wherein similar characters of reference designate corresponding parts throughout the several views thereof, the numeral 10 indicates the base of the mold, which is formed of a substantially oblong block or body of metal having a relatively wide channel-way formed in its upper face, the opposite side walls of the channel-way being under cut to provide bevelled guideways 11 for the sliding engagement therewith of similarly bevelled guideways 12 formed in the opposite side walls of a pair of mold blocks 13 and 14. After these mold blocks 13 and 14 have been positioned inwardly of the opposite ends of the base 10, end blocks 15 and 16, also provided with bevelled guideways 12' are slid into the channelway from the opposite ends thereof and are secured, by means of tapered pins or the like 17, in position with their outer end faces flush in the plane of the end faces 90 of the base 10, so that the mold blocks 13 and 14 are retained between the same during the casting or molding operations.

The mold block 14, to be hereinafter designated the tail block of the mold, is preferably abutted against the end block 16 complementary thereto at all times, while the mold block 13, to be hereinafter designated as the head block, is adjustable with respect to the tail block 14 and between the same 100 and the end block 15. The upper faces of the head and tail blocks 13 and 14 are identically formed to provide casting or molding cavities, one cooperating with the

other, and each of these cavities consist of a circular recess 19, 20, formed inwardly from the opposed edges of the blocks 13 and 14, and slotted openings 19' and 20', respectively, leading outwardly of the circular recesses 19 and 20 through the opposed edge portions of the blocks, one in alinement with the other. Formed within the circular cavities or recesses 19 and 20 of the mold blocks 13 and 14, and arranged concentrically thereof, are cylindrical studs 21, constituting cores for the forming of the usual circular terminal engaging recesses or sockets in the cast or molded battery straps. It is to be here noted, that the side walls of the cavity portions 19, 19', 20 and 20' and 25, of the mold blocks 13 and 14 and the insert blocks 24, respectively, are upwardly and outwardly inclined, while the core studs 21, disposed within the circular cavities 19, 20', of the mold blocks 13 and 14 are upwardly and inwardly tapered, whereby the complementary walls of the casted or molded article will be correspondingly formed, and the removal of the article, from the mold cavities, when sufficiently cool, will be facilitated.

To cast or mold the smallest of the battery straps, as contemplated for the apparatus, the head block 13 will be moved along the guideways 12 to bring its inner end into abutting relation with the opposed inner end of the tail block 14, when the former will be clamped in such position by a clamp screw 22, which is threaded inwardly of the end block 15, in the plane of the longitudinal center of the base 10, for the purpose, and this screw is provided at its outer end with a knurled finger piece 23 for its proper manipulation. To affect the casting or molding of the battery straps of larger sizes, insert mold blocks 24, of varying widths, are to be interposed between the opposed end faces of the head and tail blocks 13 and 14, one interchangeable for the other, and each of these inserts will have their upper faces formed with a transversely extending slot-way 25 adapted to aline with the slotted openings 19', 20', of the mold blocks 13 and 14. These insert mold blocks 24 may be placed in position by removing the end block 15, and withdrawing the head block 13 from the channel-guides 12, when the desired insert block 24 will be slid inwardly of the latter and into abutting relation with the inner end of the tail block 14, after which the head block 13 and the end block 15 will be replaced in their normally operative positions. The end block 15 will now be fastened in place by securing pins 17, and the clamp screw 22 will now be manipulated to tighten up against the head block 13 and force the same, together with the insert block 24, into abutting relation with respect to each other and to the tail block 14.

Normally overlying the upper faces of the mold blocks 13 and 14, and the end blocks 15 and 16, is an ingate consisting of an oblong metal plate 26 having a centrally disposed pouring hole 27 therein normally registering with an intermediate portion of the casting or molding cavities in the mold blocks 13 and 14. This ingate 26 is preferably pivoted at one end to a pivot pin 28 rising from the upper face of the end block 16, whereby the same may be swung to and from its operative position over the mold blocks 13 and 14, a suitable handle 29 being provided at its opposite end to facilitate the manipulation of the same for such purpose. The pouring hole 27 is preferably formed in the bottom of an inwardly tapered depression or concavity 26', formed at the center of the upper face of the ingate 26, and the wall of this hole is arranged to effect a shearing off of the excess metal remaining in the depression or concavity 26', after the pouring of the metal in molten state therethrough and into the mold cavity proper, which is readily accomplished by swinging the ingate outwardly on its pivot 28, after the mold has been allowed to cool, and the cast metal within the same has solidified sufficiently to be undisturbed by said shearing action for the removal of the excess or surplus metal therefrom as aforesaid. The pivot pin 28 is preferably headed as at 30 to retain thereon a coiled spring 31, which acts to tension the ingate 26 against free swinging movements from either of its operative or inoperative positions. To assure of the ingate 26 being positioned over the mold blocks 13 and 14 for the accurate registering of the pouring hole 27 thereof with the alined portions of the mold block cavities, a stop pin or the like 32 is passed downwardly of an opening formed in the base 10 at one side of the end block 15, and is formed to provide an upper headed end portion disposed in the path of the swinging movement of the ingate 26, and to be abutted by the same when moved to its operative position, the adjacent edge of the latter engaging under the headed portion of the pin 32, so that this headed portion may be forced downwardly to exert a clamping action thereon, when the clamping pin will be secured in its operative position by means of a set screw 33 being threaded inwardly of the end wall of the mold base 10 so that its inner end contacts the shank of the pin for the purpose.

Depending from the under side of the mold base 10, and spaced apart on the longitudinal center and equidistantly inward from the opposite ends thereof, are a pair of guide pins or rods 34 on which is slidably mounted a cross head, which consists of a bar portion 35 being disposed in parallel relation to the under face of the base 10,

and having angularly disposed feet portions 36 formed at its opposite end and engaged over the rod 34, the lower free ends of each of the latter being threaded to receive thereon 5 an inner adjusting nut 37 and a lock nut 38. The cross head is normally tensioned in a downward direction, with the lower ends of the feed portions 36 thereof abutting the adjusting nuts 37, by means of coiled springs 39 carried on the rods 34 and interposed between the upper face of the bar 35 and lower face of the mold base 10. Formed in the mold base 10 are a plurality of pairs of large and small openings 40 and 41, respectively, the individual openings of each pair thereof being spaced apart one from the other, and the pairs of larger openings 40 being spaced apart to either side of the transverse center of the mold base 10, while 10 the pairs of small openings 41 are spaced outwardly at the opposite sides of each pair of the larger openings 40, and all of the several pairs of openings 40 and 41 are disposed on the longitudinal center of the base 15 10 and in line with the longitudinal center of the bar 35 of the cross head. Similarly, the head and tail mold blocks 13 and 14 are each formed to provide large openings 42 opening upwardly of the same and into the 20 bottom wall of the circular mold cavities thereof at the inner side of the core studs 21 therein, and small openings 43 in a similar manner at the opposite or other sides of the latter, and these openings 42 and 43 are 25 adapted to be registered with correspondingly sized openings of the pairs of openings 40 and 41 of the base 10, according to the adjustment of the mold blocks 13 and 14 for the casting or molding of a particu- 30 lar size of battery strap. When the mold blocks 13 and 14 have been clamped in adjusted position for a desired casting or molding operation, a pair of larger size plungers 44 will be positioned within the 35 registering pair of the larger openings of the base 10 and the mold blocks 13 and 14, and a pair of small size plungers 45 similarly within the registering pairs of small openings, when the lower ends of the several 40 plungers 44 and 45 will rest on the upper face of the cross bar 35 of the cross head, while their upper ends will be disposed flush in the plane of the bottom walls of the molding cavities of the mold blocks 13 and 14. 45 After the casting operation, and the metal of a molded strap has cooled down to a desired degree, the cross head is to be forced upwardly in a manner to cause the plungers 44 and 45 to eject the strap upwardly of the 50 mold cavity, and for such purpose a hand lever 46 is pivoted at a point intermediate its opposite ends on a pivot pin 47 carried by a bifurcated lug 48, depending from the under side of the mold base 10, and has its 55 inner end engaged under the cross bar 35, so that by grasping the outer end of handle portion 49 of the lever, and pressing downwardly thereof, when the inner end thereof will force the cross head upwardly against the tension of the coiled springs 39, as hereinbefore indicated. 70

In the practical use of the mold device or apparatus, the same is preferably supported in desired horizontal position for operation by means of a bar 50, which is secured at one end to one side of the mold base 10, by means of screws or the like 51, and which has its other end projecting beyond the adjacent end of the base for clamping engagement between the jaws of an ordinary bench vise (not shown). With the mold blocks 13 and 14 in position, and an insert block interposed therebetween, if it is desired to cast a battery strap of a greater length than that produced in the use of the blocks 13 and 14 alone, the several larger and smaller plungers 44 and 45 are dropped into the registering openings of the head and tail blocks 13 and 14 and the base 10, and the ingate 20 25 30 35 40 45 50 55 60 65 70 75 80 85 90 95 100 105 110 115 120 125 130

26 is then swung inwardly to its operative position over the latter and is secured under the head of the lock or stop pin 32, when the device or apparatus will be ready for the casting or molding operation. The molten metal, such as lead or the like, is now poured into the pouring hole 27 and until the mold cavity as a whole is filled, as will be indicated by an excess or surplus of the metal filling or partially filling the upper concave portion of the pouring hole, and thereafter the mold is allowed to cool down. When it is desired to remove the strap casting from the mold, the lock pin 32 is loosened sufficiently to allow the ingate 26 to be swung outwardly on its pivot 28, during which swinging movement the wall of the opening of the pouring hole in the same will shear off from the strap casting the excess or surplus metal remaining in the concavity 26', which action eliminates the necessity of filing or otherwise smoothing down the top surface of the strap casting after its removal from the mold. The strap casting may now be ejected from the mold cavity, by pressing down on the hand lever 49, which action forces the cross head 35 and the plungers 44 and 45 actuated thereby in an upward direction, when the casting strap will be lifted on the upper ends of the plungers 44 and 45 forcing against the under sides thereof. When the plungers 44 and 45 have reached the upward limit of their movements, the strap casting will be held free from the mold cavity, and may now be thrown from the mold into a receptacle or the like by the swinging of the ingate 26 back to its operative position. 120

From the foregoing, it will be readily apparent that while a preferred embodiment of the mold device or apparatus has been 125 130

described and illustrated herein in specific terms and details of construction and arrangement, various changes in and modifications of the same may be resorted to without departing from the spirit of the invention, or the scope of the claims appended hereto.

Having thus fully described the invention, what is claimed, is:—

10. 1. In a molding apparatus, a base having its upper face provided with a channel way formed with undercut walls, mold bodies cooperating one with the other and mounted on said base and further extended into said channel and undercut walls, blocks mounted on the base and extended into said channels and further into said undercut walls and having said bodies interposed therebetween, means carried by one of the blocks for 20 clamping said mold bodies in operative position, and an ingate pivoted on the other of said blocks and movable to and from operative position over said mold bodies.
2. In a molding apparatus, a base having its upper face provided with a channel way formed with undercut walls, mold bodies cooperating one with the other and mounted on said base and further extended into said channels and undercut walls, blocks mounted 30 on the base and extended into said channels and further into said undercut walls and having said bodies interposed therebetween, means carried by one of the blocks for clamping said mold bodies in operative position, an ingate pivoted on the other of said blocks and movable to and from operative position over said mold bodies, an expandible and contractile element bearing against the pivoted end of said ingate, 40 and means carried by that end block provided with the clamping means for retaining said ingate in operative position with respect to said mold bodies.
3. In a molding apparatus, a base, apertured mold bodies cooperating one with the other and mounted on and extending into the base, said base and bodies having cooperating means for connecting the bodies to the base, end blocks mounted in said base 50 and having said bodies interposed therebetween, said base and end blocks having cooperating means for connecting them together, said base formed with a plurality of openings adapted to register with certain of the openings in said bodies, vertically disposed casting removing elements extending through the registering openings and further closing the openings in said bodies, a 55 spring controlled inverted yoke-shaped member suspended from said base and bearing against the lower ends of said elements, an ingate pivoted to one of said end blocks and movable to and from operative position over said mold bodies, means carried by the other of said end blocks for maintaining 60
- 65

said ingate in operative position, and shiftable means suspended from said base and engageable with said member for shifting said elements to remove the casting from the mold bodies.

4. In a molding apparatus, a base, apertured mold bodies cooperating one with the other and mounted on and extending into the base, said base and bodies having cooperating means for connecting the bodies to the base, end blocks mounted in said base and having said bodies interposed therebetween, said base and end blocks having cooperating means for connecting them together, said base formed with a plurality of openings adapted to register with certain of the openings in said bodies, vertically disposed casting removing elements extending through the registering openings and further closing the openings in said bodies, a spring controlled inverted yoke-shaped member suspended from said base and bearing against the lower ends of said elements, an ingate pivoted to one of said end blocks and movable to and from operative position over said mold bodies, means carried by the other of said end blocks for maintaining said ingate in operative position, shiftable means suspended from said base and engageable with said member for shifting said elements to remove the casting from the mold bodies, and means extending through said end blocks and engaging in the base for fixedly securing said end blocks in position.

5. In a molding apparatus, a base, apertured mold bodies cooperating one with the other and mounted on and extending into the base, said base and bodies having cooperating means for connecting the bodies to the base, end blocks mounted in said base and having said bodies interposed therebetween, said base and end blocks having cooperating means for connecting them together, said base formed with a plurality of openings adapted to register with certain of the openings in said bodies, vertically disposed casting removing elements extending through the registering openings and further closing the openings in said bodies, a spring controlled inverted yoke-shaped member suspended from said base and bearing against the lower ends of said elements, an ingate pivoted to one of said end blocks and movable to and from operative position over said mold bodies, means carried by the other of said end blocks for maintaining said ingate in operative position, shiftable means suspended from said base and engageable with said member for shifting said elements to remove the casting from the mold bodies, means extending through said end blocks and engaging in the base for fixedly securing said end blocks in position, and means carried by that end block 120

provided with means for retaining the ingate in operative position for clamping said mold bodies in operative position.

6. In a molding apparatus, a base, apertured mold bodies cooperating one with the other and mounted on and extending into the base, said base and bodies having cooperating means for connecting the bodies to the base, end blocks mounted in said base and having said bodies interposed therebetween, said base and end blocks having cooperating means for connecting them together, said base formed with a plurality of openings adapted to register with certain of the openings in said bodies, vertically disposed casting removing elements extending through the registering openings and further closing the openings in said bodies, a spring controlled inverted yoke-shaped member suspended from said base and bearing against the lower ends of said elements, an ingate pivoted to one of said end blocks and movable to and from operative position over said mold bodies, means carried by the other of said end blocks for maintaining said ingate in operative position, shiftable means suspended from said base and engageable with said member for shifting said elements to remove the casting from the mold bodies, and an expansible element bearing on the pivoted end of said ingate.

7. In a molding apparatus, a base, apertured mold bodies cooperating one with the

other and mounted on and extending into the base, said base and bodies having cooperating means for connecting the bodies to the base, end blocks mounted in said base and having said bodies interposed therebetween, said base and end blocks having cooperating means for connecting them together, said base formed with a plurality of openings adapted to register with certain of the openings in said bodies, vertically disposed casting removing elements extending through the registering openings and further closing the openings in said bodies, a spring controlled inverted yoke-shaped member suspended from said base and bearing against the lower ends of said elements, an ingate pivoted to one of said end blocks and movable to and from operative position over said mold bodies, means carried by the other of said end blocks for maintaining said ingate in operative position, shiftable means suspended from said base and engageable with said member for shifting said elements to remove the casting from the mold bodies, means extending through said end blocks and engaging in the base for fixedly securing said end blocks in position, and an expansible element bearing on the pivoted end of said ingate.

In testimony whereof, I affix my signature hereto.

THOMAS E. JONES.
